Asa Burgess & Herman. Baldwin &
Washington, Litchfield County, State of Connecticut.

Letter Patent.

The schedule referred to in their Letter Patent and making
part of the same, containing a description in the words of the
said Asa Burgess & Herman Baldwin themselves of their
improvement in the machine for threshing and cleaning clover
and Timothy seed.

Be it known that we Asa Burgess and Herman
Baldwin both of Washington in the County of Litchfield in
State of Connecticut have invented a new and useful improve-
ment in the machine for threshing and cleaning Clover and
Timothy seed, and that the following is a full and exact de-
scription of the construction and operation of said machine and
specification of the said improvement therein.

The machine consists of an upright frame of
timber about four inches square and seven feet three inches
high connected by girders of the same size and covered inside
of the posts with boards in panels so as to form an upright
box three feet by two feet and a half in the clear from
top to bottom, on to the tops of these posts are framed two
timbers of the same size extending across the shortest side of
the top of the box and beyond the posts on the front side of
the machine two feet, the last mentioned timbers are connected
together at their outer ends by a cross timber of the same di-
mensions, a cylinder of wood or iron two feet ten and
a half inches long, and eighteen inches in diameter fitted
on its surface with molten points or teeth one fourth of an
inch long and one inch apart, set in the form of diamonds
is placed within said box with its eyes on the cross timber

of the original frame in box, the front and rear ends of the bottom of said frame or box, the front of the cylinder, and the rear of the box, next to the ends of the cylinder, are all cut out to take points, in the same manner as the top of the cylinder. These pieces of iron also project from the end of the cylinder about half an inch toward the body of the box. They are two inches long, and run from the circumference in a diagonal line cutting segments of about one-fifth of the circumference of the cylinder. The object of these pieces of iron being to throw out of the space between the ends of the cylinder and the body of the box, the shavings and dust which would otherwise accumulate there during the machine in its operation. And it is to be understood that there are to be no points in the body of the box directly opposite to these pieces of iron. The molten points above mentioned are made of steel slightly hooked, flattened, and long, the shank being round and half of the circumference of the point being flat and the head half round and iron punched so as to obtain a thickness of one-half inch at the head, in a very similar manner. The inventor considers that the first above described, as preferable to any others, as the central bar is fixed within the box about one inch and a half below the lower of the lower side of the cylinder, extending from the front point inward to a point half way between the perpendiculars of the porphyry and the body of the axis of the cylinder, and that the upper edge of this bar is formed of a perpendicular piece of steel one-eighth of an inch thick extending along the whole length of the cylinder, its upper edge being one eighth of an inch distant from the point of the cylinder. Directly under the cylinder, along its whole length, and from side to side of the box is a concave shoe forming one third of a circle, its inner surface filled with molten points in the same manner as the cylinder. Its distance from the cylinder directly under the axis thereof, is one inch from this point toward the axis.

up to it approaches gradually nearer to the cylinder to the distance of three feet from the nearest part of the front or lower edge of the box, it should be the same size of box, and of length and width proportionate to the horizontal line of the sides of the cylinder. The box should be placed in a mean plane of four and a half inches each of its ends, and bent so as to embrace it on every side, the arms are connected with the sides of the box near the middle by a picket or pins, and so to bend the top of the box over the end of the cylinder being set down upon it, so as to keep the box in its place, and the same time allowed to yield to any movement, just such as may be required, and upon the top of the box may be made a seat for the rider of the cylinder, upon which the rider will be conveniently placed to prevent the collection of dirt or other substance, will be found in its bottom length, a flat, thin plate of iron, which should be bent horizontally toward the cylinder, and forth of it, and bent so as to run from the ends of the box, just so as to the left of the cylinder.

The rider or man should be placed to prevent the staff and case from falling out, the space between the ends of the cylinder and the sides of the box, as also and the space between the end of the box, covering the ends of the cylinder, as may be made, may be covered with a thin plate of iron, about half an inch to cover the space between the ends of the cylinder and the sides of the box, and about half an inch of the cylinder, and in case the cylinder is to be used in the water, the same should also cover the top of the box, and be fastened on this inner side, centered down the lower part of the box, a space of about two inches between them and the upper edge of the box being left open to allow the staff and case to be easily got into the space between the ends of the cylinder and the sides of the box, to work out again from the same aperture in the

A perpendicular sleeve is made of the metal and passes through the top of the top part made of the metal post and passes down to the oblique base above described. The sleeve is made of metal and passes through the sleeve forming the top part and passes down to the bottom of the sleeve, 11 mm from the top of the sleeve and is parallel with the under side until it meets the perpendicular sleeve above mentioned, meeting the sleeve and passes with this and meets up with each other on the sleeve. There is a separator made of the big and extending right through the top part and the bottom part of the cylinder. It is placed close to the perpendicular sleeve. It is attached at its upper edge to the sleeve, and by a clockwise motion of the distance from the top of the top to the cylinder by a portion which fits into and it extends downwards so far when it is moved over the cylinder.

15 hours ago. The cylinder is cast from the cylinder in front
the main cylinder. The cylinder is 10 inches in diameter and 12 inches high. The cylinder
is composed of a large number of small cylinders which are
1/2 the size of the main cylinder. The cylinder is
placed in a box.

The cylinder is composed of a large number of small cylinders
and about 1000 small cylinders of 1/2 the size of the main cylinder. The cylinder
is 10 inches in diameter and 12 inches high. The cylinder
is composed of a large number of small cylinders which are
1/2 the size of the main cylinder. The cylinder is
placed in a box.

The cylinder is composed of a large number of small cylinders
and about 1000 small cylinders of 1/2 the size of the main cylinder. The cylinder
is 10 inches in diameter and 12 inches high. The cylinder
is composed of a large number of small cylinders which are
1/2 the size of the main cylinder. The cylinder is
placed in a box.

the horizontal line of the top of the cylinder and extends down-
ward in an oblique direction toward the top of the cylinder
one foot and eight inches from the place where it starts, the
box 16 inches wide being divided into four sections
of 4x4 from the top of the top of the box upwards and back-
wards on the down slope of the cylinder 12 inches within the top three
feet and one half.

The other three sides of the conductor are to the same height from the top of the board but do not enter it at all and the outer end of the board is provided by a wheel when it opens, to permit the escape of the wire if it gets entangled filling the latter space between the board and the top of the box and opening below on to a view of the pipe between through which the wire is passing, passes the pipe and through the central space formed by the wheel and board onto the floor below. The floor is covered with a mat of fine wire mesh which has a mesh of one-half inch square and is provided with a white insulation of the same size. A small hole is made in the floor to give it the required motion. The door is provided with a bottom of the upright type and is located so as to prevent the escape of the shaff and dust from the machine. On the right side the conductor provided for the purpose of the door are places of panels of conductors of iron and copper which are turned and recessed by pressure and are held in place by a rivet of being easily removed and replaced when necessary for the purpose of cleaning and passing the machine over other purposes.

the floor, which was placed on the lower floor of a
two-story building, of seeing just above the floor of
the second story, and the upper part of the perpendicular
staircase above described, which was a stone staircase above
the boy, he attached a pulley, which passed over a block
above and thence through the floor into the lower story.

which is often the case. The conductors are made of
thin flat squares of mica, and the
openings through the sides of the building
in an proportionate and three of these
are placed in series, and the
rough side of each is turned
or placed to the glass, so that
performs the two functions of insulating
and reflecting the light. The glass
is about 1/4 inch thick, and the
conductors are about 1/16 of an inch wide
and 1/16 of an inch apart, so that the
conductors are increased
in dimensions, and the
heat of the glass is increased
when the heat is applied to the glass, and
it is also increased when the
heat is applied to the conductors, and
they are so arranged as to be
able to draw off the heat
from their cells, and then to draw off through the conductors

on the outside of the building, while the seed falls down through the air apparently as though it were sent into the floor below. It is necessary, however, to pay attention to the seed after this operation, as it may be necessary to re-apply it to perfect it through a common powdering mill, in order to make it perfectly clean. In cases of untraded heads of grain, fall down through the air apparently half off, so the sides of the stems, they are to be again put into and passed through the machine.

The top of frame or top of frame to place
on the floor of the building by the oldest waggon
16. seconds of immovable and moveable metal of the
several parts of the machine may be increased in the
relative proportion but cannot be materially diminished
without injury.

Specification and description of the whole of the machine and its improvement therein as hereinafter described, on the 20th day of October, 1835.
